UNITED STATES PATENT OFFICE

134,052

DESIGN FOR A TWINE CONTAINER

William R. Neill, Valley Station, and Marshall T. Minor, Louisville, Ky.

Application April 29, 1942, Serial No. 106,752

Term of patent 14 years

To all whom it may concern:

Be it known that we, William R. Neill and Marshall T. Minor, citizens of the United States of America, residing at Valley Station, in the county of Jefferson and State of Kentucky, and Louisville, in the county of Jefferson and State of Kentucky, respectively, have invented a new, original, and ornamental Design for a Twine Container, of which the following is a specification, reference being had to the accompanying drawing, forming part thereof, wherein—

Figure 1 is a perspective view of a twine container, showing our new design.

Figure 2 is a top plan view.

We claim:

The ornamental design for a twine container, as shown.

WILLIAM R. NEILL,
MARSHALL T. MINOR.
